2 Claims. (Cl. 91—204)

This invention relates to rotary machines of the type comprising a centrally arranged pintle acting as a valve, a rotor mounted on the pintle and provided with cylinder spaces each of which has a port which cooperates with the pintle and during rotation of the rotor on the pintle is successively connected to and disconnected from an inlet duct and an outlet duct in the pintle, and a ring mounted eccentrically to the pintle said ring surrounding the rotor and engaging pistons which are movable in the cylinder spaces and during rotation of the rotor are propelling the ring and at the same time are reciprocated thereby between two dead centre positions. In particular, the invention relates to a construction of the type in which the machine acts as a motor and the working medium of which is a compressed gaseous medium, such as compressed air. In order to have the machine operated in the most favourable manner, the cylinder spaces must be put into communication with the inlet and outlet in exact accurate position of the pistons during the cycle of operation. This position varies with the pressure, speed and piston stroke if said stroke is variable. It may also be advantageous to interrupt the communication between the cylinders and the ducts during part of the cycle of operation, the gas enclosed in the cylinder spaces expanding or being compressed during said part. By selecting suitable opening angles of the pintle it is easily possible in this manner to obtain an optimum operation of the motor for given conditions. However, there are often different stipulations requiring change of the operation of the motor, for instance increase or decrease of the torque or reversal of the direction of rotation. Such changes are suitably obtained by varying the eccentricity of the ring relative to the pintle which means that the axis of rotation of the rotor has to be displaced relative to the axis of the surrounding ring. A simple, inexpensive and practical manner to realize this fact consists in a translational displacement of the pintle. The object of the present invention is to provide a device which renders possible displacement of the pintle in a manner such as to maintain favourable datum angles of the pintle at varying eccentricity and clockwise as well as counter-clockwise rotation.

In the broadest aspect of the invention the pintle is guided relative to the ring by means which render possible translational displacement of the pintle while maintaining a certain angular displacement of the pintle—datum angle—relative to the angular position of the rotor in which the piston changes its direction of motion, with or without change of said datum angles during displacement. The datum angle may be selected such that a pre-compression is obtained and that the pressure due to said precompression in the cylinder space inside the piston is equal to the pressure which prevails in the inlet duct of the pintle when the port is opening into said cylinder space. If in case of equidistantly located cylinders in the rotor the distances between the ports and the cylinders are equal and the ports are suitably spaced apart, favourable condition of admission similar in character will be obtained in all cylinders resulting in the highest average pressure possible in the motor as well as the highest torque possible.

2

Suitable adjustment of the above named datum angle is dependent on the working pressure in the inlet of the motor the speed of the rotor and the stroke of the pistons. There exists one setting only which suits a given condition 5 of operation and a given direction of rotation. On reversing the direction of rotation the datum angle has to be changed if the same conditions are to be obtained as in the case of the original direction of rotation and with other factors remaining constant. This is a difficult operation 10 if the pintle first has to be adjusted with respect to the eccentricity and thereupon has to be turned. In accordance with an important development of the inventive idea the direction of rotation can be reversed in a very simple manner solely by a rectilinear displacement of the pintle 15 relative to the casing of the motor in which the eccentric ring is journaled.

The invention is explained more closely with reference to the drawing in which FIG. 1 is a diagrammatic sectional view taken parallel to the axis of a motor constructed in accordance with the invention. And FIG. 2 shows the pintle in a similar section and a diagram illustrating the conditions on reversal of the direction of rotation. FIGS. 3 and 6 are diagrammatic radial sectional views and FIGS. 4, 4a and 5 are diagrams.

25 Referring to the drawing numeral 1 denotes a pintle and numeral 2 a rotor mounted for rotation on the pintle and having cylinder spaces 3 for pistons 4 which are radially movable in the cylinder spaces relative to the axis of rotation σ of the rotor, six pistons being provided in the 30 form of balls. The balls are in contact with recesses 5 of a roll race formed on the internal side of surrounding ring 6 which like the rotor 2 is mounted in the frame or casing (not shown) of the motor so as to be rotatable about an axis σ' which is located eccentrically with respect to the pintle 1. The pintle has longitudinally extending recesses forming an inlet duct 7 for a compressed gaseous medium, preferably compressed air and an outlet duct 8 for discharged working medium. During rotation of the rotor the ring 6 is propelled by the balls 4 which 35 engage the recesses 5 on the internal side of the ring and act both as pistons and as locking members. Due to the eccentricity of the ring 6 relative to the pintle and the rotor the balls will move during each revolution from an inner dead centre assumed by the ball 4a outwards in the cylinder space to an outer dead centre position as assumed by the ball 4b. The cylinder spaces communicate with ports 9. During one revolution each port passes successively the inlet duct 7, a pintle surface 10, the outlet duct 8 and a pintle surface 11. The stroke of the pistons 40 equals twice the eccentricity which is the distance between σ and σ' .

The recesses in the pintle 1 which form the inlet duct 7 and the outlet duct 8 are bounded by plane parallel surfaces 12 and 14, located at different distances from the axis of rotation σ such that the cross-sectional area of the inlet duct 7 is smaller than that of the outlet duct 8.

55 The diagram shown in FIG. 2 illustrates the pintle 1, the plane surfaces 12 and 14 of the pintle which bound the inlet duct 7 and the outlet duct 8 and a cylinder port in different positions 9a, 9b, 9c and 9d. The ring 6 is denoted by chain-dotted circles 6a, 6b which show two different positions of the ring, namely, a position in which the ring (together with the rotor) rotates about a centre 60 A in the direction indicated by the arrow RA and another position in which it rotates about a centre B in the direction indicated by the arrow RB. A plane of symmetry of the pintle at a right angle to the plane surfaces 12, 14 thereof is indicated by a chain-dotted line 15. The angular position in which the piston is at its inner dead centre is indicated at VA for the direction of rotation RA and at VB for the direction of rotation RB. In the position 9a the port is about to be connected to the inlet

7, and in the position 9b the port has just been covered. The angle between these positions, that is, the inlet angle is indicated at α . In the position 9c the port is about to be connected to the outlet 8 and in the position 9d it has just been covered. The angle between these positions, that is, the outlet angle is equal to $\alpha+2\delta+2\gamma$ wherein δ is the angle through which the centre of the port moves from the inner dead centre position VA to the position in which the port is about to be connected to the inlet, and γ is the angle through which the centre of the port moves from the moment when the communication with the outlet duct 8 is about to be opened to the outer dead centre position (which is the position of the rotor in which the corresponding piston assumes its corresponding dead centre position). β is the angular distance during which compression and expansion, respectively, of the working medium takes place in the cylinder space.

It will be seen from FIG. 2 that if the rotor is driven clockwise the pintle is positioned at an angle equal to

$$90 - \frac{\alpha}{2} - \delta$$

degrees from the direction of rotation as measured from the inner dead centre position VA. The same angle starting from the position VB is obtained in case of counter-clockwise rotation. Since in this case the inlet 7 is located on the same side of the pintle, α , β and $\alpha+2\gamma+2\delta$ will be the same for both directions of rotation which means that all of the characteristic angles will be unchanged irrespective of the direction of rotation. In FIGURE 2 the datum angle is defined by the intersection of a line through the center of rotation o of the rotor and the center of rotation A of the cylinders and a line through o and through the axis of the cylinder at 9a where the cylinder is about to be uncovered at the inlet. Thus, the datum angle is shown at δ .

Usually the ring 6 is rotatably but non-displaceably mounted in the casing of the motor whereas the pintle and the rotor are transversely displaceable in the casing for varying the eccentricity and consequently the stroke of the pistons. As will be apparent from FIG. 2, reversal of the direction of rotation is obtained by displacing the rotor and the pintle relative to the ring such that the axis of rotation of the ring coincides with the point B instead of the point A or vice versa. Consequently, the most simple way of reversing the motor is to move the rotor and pintle parallel to the line AB which in the embodiment illustrated is parallel to the plane surfaces 12 and 14, which bound the inlet and outlet ducts. For maximum piston stroke the eccentricity $E_A=E_B=E$ which means that the eccentricity in the position A is equal to the eccentricity in the position B. The perpendicular distance between the axis o of rotation of the rotor and the line AB is denoted at e , which distance may be considered the eccentricity of the ring at right angles to the surfaces 12 and 14 of the pintle. The relation between e and E according to FIG. 2 is given by the equation

$$e = E \cos \left(\frac{\alpha}{2} + \delta \right)$$

A characteristic way of rendering possible rectilinear displacement is shown in FIG. 3 in which numeral 16 denotes a bearing for the pintle 1 and numeral 18 denotes a pair of radial pins which are connected to the bearing and by means of which the bearing can be displaced relative to the motor casing 17. The bearing has bores 19 for the pins 18 which upon displacement of the pintle are moved in their longitudinal direction. The centre o of the pintle is rectilinearly displaceable from an end position shown in FIG. 3 to the right of the diametrical plane 20 of the casing to a point o_2 at equal distance to the left from the diametrical plane without change of the eccentricity e .

Displacement of the pintle need not take place along 75

a single straight line. If it is desired to maintain the datum angle constant for different values of the eccentricity E the device is constructed as principally shown in FIGS. 4 and 4a. FIG. 4 illustrates a pintle diagram similar to that shown in FIG. 2, and from FIG. 4a it is to be seen that the ring is not displaced directly from A to B, but rectilinearly from A to o and thereupon rectilinearly from o to B. It can be seen directly from FIGS. 4 and 4a that the datum angle remains unchanged during displacement, whereas E is varying. When the center of rotation of the cylinders is displaced from A to o to B the eccentricity progresses from positive maximum to zero to negative maximum.

FIG. 5 illustrates in a diagrammatic way displacement from A to B along a curved line which is symmetrical with respect to a line y—y. In case of such a displacement the angles β and γ are decreased with decreasing E, whereas δ is increased.

For practical performing of the displacement according to FIG. 5 a construction schematically shown in FIG. 6 may be used. As compared with FIG. 3 the straight bores 19 for the pins 18 are replaced by curved races 21 for guide rollers 22 which are rotatably mounted on radial arms 23 of the bearing 16 for the pintle 1. Numeral 24 denotes the curved line, along which the centre o of the pintle is moved.

As will appear from the above, the present invention opens the possibility of selecting optimum and equal conditions for both directions of rotation which is very important for instance in case of high speed motors for the purpose in consideration where the motor is required to be able to run in both directions of rotation without changes of performance. It is not possible to obtain top speeds of the order of 75,000 r.p.m. or more without attending to the described optimum regarding the datum angle. For this reason the invention described is highly advantageous if it is desired to reverse the direction of rotation in a simple manner while maintaining predetermined performance data constant.

The above described arrangements are examples only of the invention. While the pintle illustrated has plane boundary surfaces 12, 14 at the inlet and outlet ducts, other shapes may be used and may be more suitable in certain cases.

What is claimed is:

1. In a rotary machine having a fluid-working medium, a pintle having opposite surfaces defining inlet and outlet openings for said medium, a rotor rotatably mounted on the pintle and having cylinder spaces and ports, a said port communicating with each of said cylinder spaces, the pintle comprising a valve to connect and disconnect said inlet and outlet openings with the cylinder spaces successively by way of said ports during rotation of the rotor on the pintle, a ring encompassing the rotor, pistons mounted in the cylinder spaces for reciprocation radially therein, the ring retaining the pistons in said piston spaces, means for mounting the rotor and the ring so that their centers are spaced apart in one direction, and means for moving the axes of the rotor and the ring relative to each other between first and second positions such that the axes of the rotor and the ring in said first position lie in a first plane and the axes of the rotor and the ring in said second position lie in a second plane and said first and second planes are disposed at a substantial angle to each other.

2. A machine as claimed in claim 1, said opposite surfaces of said pintle having end edges adjacent said rotor, the end edges of one of said surfaces being disposed in a third plane parallel to said axes, the end edges of the other of said surfaces being disposed in a further plane parallel to said axes, said third and fourth planes being parallel to each other, and said first and second planes forming equal and opposite angles with said third and fourth planes in said first and second positions.
